UNITED STATES PATENT OFFICE.

WILBUR LLOYD ROUNDS, OF RENSSELAER, NEW YORK.

HYDRAULIC TRANSMISSION.

1,258,468.

Specification of Letters Patent.

Patented Mar. 5, 1918.

Application filed March 9, 1917. Serial No. 153,597.

To all whom it may concern:

Be it known that I, WILBUR L. ROUNDS, a citizen of the United States, and a resident of Rensselaer, in the county of Rensselaer 5 and State of New York, have invented a new and Improved Hydraulic Transmission, of which the following is a full, clear, and exact description.

This invention relates to hydraulic transmission of that type disclosed in the application for United States Letters Patent Serial No. 82,109, filed March 4, 1916, in which the driving element is in the form of a paddle wheel revolving within a casing 10 which is the driven element and which has on its internal peripheral surface, vanes against which the hydraulic medium set in motion by the paddle wheel operates to cause the casing to be driven. 15

20 The invention has for its general objects to improve the construction and operation of transmission of the character referred to so that it is adaptable for automobile or other work requiring a varying amount of power and varying speeds, and which enables the power to be easily thrown on or off by the paddles or impeller blades being adjustable to different angles; that is to say, by presenting the flat faces directly to the hydraulic medium or their edges thereto.

25

A more specific object of the invention is the provision of a novel form of impeller which is provided with a plurality of spaced blades arranged in groups, with the blades 30 of each group being operatively connected together, and the groups being connected with an adjusting means located outside the clutch, whereby all the blades can be adjusted to have their maximum effect on the 35 hydraulic medium or no effect.

With such objects in view, and others which will appear as the description proceeds, the invention comprises various novel features of construction and arrangement of 40 parts which will be set forth with particularity in the following description and claims appended hereto.

In the accompanying drawings, which illustrate one embodiment of the invention 45 and wherein similar characters of reference indicate corresponding parts in all the views,

Figure 1 is a sectional view taken parallel with the axis of rotation and with portion of 50 the casing in elevation, the section being taken on the line 1—1, Fig. 2;

Fig. 2 is a transverse section on the line 2—2, Fig. 1;

Fig. 3 is a fragmentary sectional view showing one group of the blades adjusted 60 to zero position; and

Fig. 4 is a detail view of the vanes to show the action of the fluid thereon.

Referring to the drawings, A designates the driving element of the transmission and 65 B the driven element which are connected respectively with the driving and driven shafts 1 and 2. The driven element B is in the form of a casing having pressed-out heads 1' and 2' and a cylindrical wall 3 70 which is integral with the head 1', and to which the peripheral portion of the head 2' is fastened with a lapped joint at 4. Secured to the heads are bearing hubs 5 and 6 for the driving shaft 1, and on the outside 75 of the head 1' is fastened by means of the flange 7 the driven shaft 2. On the inner surface of the circumferential wall 3 are sets of vanes 8, 9 and 10, the latter being disposed at opposite sides of the central set of 80 vanes 8, the sets of vanes 9 and 10 being opposite each other and in staggered relation to the vanes 8.

The impeller element A comprises a pair of spaced disks 11 and 12, between which 85 are pivoted the paddles or blades 13, the latter having pivots 14 journaled in openings 15 in the disks. Each blade 13 has a crank arm 16 at one end and lying between the disks. The blades 13 are divided into four 90 groups of three each when twelve blades are employed, as shown in Fig. 2, and the cranks 16 of the blades of each group are united with a common connector 17, the cranks of each group of blades being sub- 95 substantially parallel and about forty-five degrees to the central blade of the group when the blades are in radial position, as shown in Fig. 1. Associated with each connector 17 is a shaft 18 having its ends 19 journaled in 100 the disks 11 and 12, and this shaft is connected by a crank 20 and pin 21 with the associated connector 17, so that by the rocking of the shaft the connector will be shifted from the position shown in Fig. 2 to that 105 shown in Fig. 3, or vice versa, whereby the blades will be adjusted from maximum to minimum driving effect.

The blade adjusting shafts 18 are adapted to be actuated by means outside the transmission, and for this purpose a collar 22 is axially slidable on the driven shaft 2, the 110

collar being rotatable with the shaft by means of a key 23 which passes through a longitudinally extending slot 24 in the driven shaft and which is connected with the 5 collar 22. The key 23 also passes through a pin 25 which is slidable in the bore 26 of the driven shaft, and this pin is arranged in end to end relation with a pin 27 slidable in the bore 28' of the driving shaft. Passing 10 transversely through the pin is a key 28 disposed in the longitudinal slots 29 and 30 of the driving shaft 1, and the hub 31 of the impeller A. Surrounding the hub 31 is a spider 32 which has its hub provided with 15 an annular groove 33 into which the ends of the key 28 engage, whereby the movement of the key back and forth will laterally shift the spider 32. This spider 32 is operatively connected with the shafts 18 so as to 20 turn the latter as the spider moves laterally. For this purpose the outer ends of the arms of the spider have rigidly clamped thereto by means of clips 34 the nuts 35, and engage helical threads 36 on the shafts 18. By this 25 means the lateral movement of the nuts with the spider turns the shafts 18 in one direction or the other for adjusting the pitch of the blades 13. The adjusting collar 22 is provided with a peripheral groove 37 into 30 which a bifurcated lever (not shown) may be engaged so that the operator can control the clutch. A spring 38 returns the spider to normal position.

The hydraulic medium, such as castor oil 35 or the like, is supplied to the transmission in such volume that when the transmission is operated the oil will form an annular belt around the interior of the casing, and of such radial depth as to cover the impeller blades 40 13, as well as the blades 8, 9 and 10 on the driven element. When the blades 13 are in the position shown in Fig. 2 they have their maximum effect on the hydraulic medium, setting the same in motion, which in turn 45 drags the driven element around with the impeller. When the blades are adjusted to the position shown in Fig. 3 they cut through the hydraulic medium without causing the latter to produce any dragging effect 50 on the driven element of the transmission, so that there will be no transmission of power through the latter.

In use, the blades will occupy either the position shown in Fig. 2 or that shown in 55 Fig. 3, but no intermediate position, but nevertheless the speed ratio will automatically change according to the load. When the transmission is pulling only a light load the driven element will run practically in step or synchronously with the driving element, but as the load is increased, the driven element lags more and more behind the driving element, but the pull is increased owing to the greater reaction of the hydraulic medium against the blades 8, 9 and 10. When

this takes place the hydraulic medium is forced to take zigzag courses through the blades 8, 9 and 10, as indicated by the arrows in Fig. 4. Thus, the hydraulic drive acts as an automatic change-speed gear. In driving 70 a car equipped with the hydraulic transmission, the driver after starting does not have to change gears or release the transmission, except when he wishes to stop, as the transmission automatically assumes a gear ratio 75 suitable to the road being traveled or the speed at which the engine is being run.

From the foregoing description taken in connection with the accompanying drawings, the advantages of the construction and 80 method of operation will be readily understood by those skilled in the art to which the invention appertains, and while I have described the principle of operation, together with the device which I now consider to be 85 the best embodiment thereof, I desire to have it understood that the device shown is merely illustrative and that such changes may be made when desired as fall within 90 the scope of the appended claims. 90

Having thus described my invention, I claim as new and desire to secure by Letters Patent:

1. A transmission comprising a driven element having vanes, a driving element having 95 pivoted blades, cranks on the blades, a plurality of connectors uniting the blades in groups, and means for adjusting the position of the connectors to vary the pitch of the blades. 100

2. A transmission comprising a driven element having vanes, a driving element having pivoted blades, cranks on the blades, a plurality of connectors uniting the blades in groups, rotatable shafts movable with and 105 movable independently of the connectors for adjusting the position of the latter to change the pitch of the blades, and means for actuating the shafts. 110

3. A transmission comprising a driven element having vanes, a driving element having pivoted blades, cranks on the blades, a plurality of connectors uniting the blades in groups, rotatable shafts movable with and 115 movable independently of the connectors for adjusting the position of the latter to change the pitch of the blades, an axially movable spider operatively connected with the shafts to rotate the same, and means for actuating the spider. 120

4. A hydraulic transmission comprising a casing rotatably mounted and having vanes, an impeller mounted in the casing and having adjustable blades, a device rotatable with the impeller and operatively connected 125 with the blades for changing the pitch thereof, means movable axially of the impeller for adjusting the device in one direction, spring means for moving the device in the opposite direction, nuts carried by the device, and

shafts carried on the impeller and having spiral threads engaged with the nuts and also operatively connected with the blades for adjusting the same.

- 5 5. A transmission comprising a rotatably mounted casing having vanes, a shaft connected with the casing, a member axially slideable on the shaft, a member slideable in the shaft and connected with the first-mentioned member, a driving shaft in the casing, a member engaging the second-mentioned member and movable axially thereby, a spider operatively connected with the third-mentioned member to slide axially of 15 the driving shaft and to rotate therewith, a spring yieldingly opposing the movement of the spider in one direction, pivoted blades

carried by the driving shaft, nuts carried by the spider, shafts having spiral threads engaging the nuts, cranks on the shafts, connectors operatively connected with the cranks, cranks on the blades, and connections between a plurality of blade cranks and each connector. 20

6. A hydraulic transmission comprising a 25 driven element in the form of a casing having three sets of vanes on the inner surface of its peripheral wall, one set of vanes being disposed between the other two sets and in staggered relation thereto, and an impeller 30 rotatably mounted in the casing to operate on the vanes through a hydraulic medium.

WILBUR LLOYD ROUNDS.
